UNITED STATES PATENT OFFICE.

RAMON GONZALEZ, OF MANILA, PHILIPPINE ISLANDS.

SELF-CLOSING MATCH BOX.

Application filed August 7, 1920, Serial No. 401,370. Renewed October 26, 1922. Serial No. 597,139.

To all whom it may concern:

Be it known that I, RAMON GONZALEZ, residing at Manila, Philippine Islands, have invented new and useful Improvements in 5 Self-Closing Match Boxes, of which the following is a specification.

This invention relates to match boxes and has for its object the provision of a match box which is provided with a spring interposed between the casing or shuck and the tray, the purpose of the spring being to close the box when its use is no longer desired and consequently prevent the box from being accidentally opened and the matches from 10 being spilled in the pocket.

An important object is the provision of a match box of this character in which the shuck or casing is formed with a plurality of ears which are stamped out and bent and 20 designed for retaining upon the sides of the shuck the abrasive chemically treated strips upon which the matches may be struck, it being observable that the device is intended primarily for the use of safety matches.

25 An additional object is the provision of a device of this character which is simple and inexpensive in manufacture, efficient in use, durable in service, and a general improvement in the art.

30 With the above and other objects and advantages in view, the invention consists in the details of construction to be hereinafter more fully described and claimed, and illustrated in the accompanying drawings in 35 which—

Figure 1 is a perspective view of the device in closed position,

Figure 2 is a perspective view showing it in open position,

40 Figure 3 is a cross sectional view, partly illustrating the formation of the abrasive strip retaining lugs or tongues, and

Figure 4 is a bottom plan view with the shuck broken away.

45 Referring more particularly to the drawings, I have shown my device as including a rectangular casing or shuck 10 which is formed preferably of sheet metal and of any desired size though in actual practice it is

50 preferable that the device be formed of a size suitable for containing matches of the so-called safety type. At its opposite ends the shuck is formed with retaining lugs 11.

55 At its longitudinal edges the shuck is cut and stamped to provide a plurality of

tongues 12 which are arranged in series and which are bent outwardly in slightly spaced relation to the sides of the shuck to serve as retaining means for removable strips 13 coated with the usual chemically treated 60 abrasive material upon which safety matches may be struck. At its corners the shuck is formed with relatively small lugs 14 which prevent longitudinal displacement of the strips 13.

Disposed within the shuck 10 is the match holding tray 15 which is also preferably formed of sheet metal and which is of a size to slide easily within the shuck. The tray is 65 of considerably less thickness than the shuck 70 so as to provide a space between its bottom and the adjacent wall of the shuck or casing and within which space is disposed a spring 16 similar in construction to a clock spring and formed serpentine in form with its convolutions extending substantially across the bottom of the tray. Under ordinary conditions the endmost convolution of the spring 75 engages against the retaining lugs 11 at the ends of the shuck. The end walls 17 of 80 the tray extend beyond the bottom thereof and are recessed, as shown at 18, for the accommodation of the lugs 11 and to define spaced lugs 19 which engage the endmost convolutions of the spring.

85 In the use of the device, matches are disposed within the tray 15 in the ordinary manner. It will be observed that the spring 16 engaging the lugs 11 and the lugs 19 will, under ordinary circumstances, operate to hold the tray entirely within the shuck so 90 as to prevent spilling of the matches when the device is carried in the pocket of the user. When it is desired to withdraw any of the matches it is merely necessary that the operator grasp the shuck and press one finger against one end of the tray whereupon the tray will be slid with respect to the shuck to have one end extending therebeyond, the spring 16 being of course compressed between the lugs 19 at the end of the tray engaged by the finger and the retaining lugs 11 at the opposite end of the shuck. When the operator releases pressure the 95 spring will operate to return the tray to normal position entirely within the shuck. As the construction is identically the same at both ends of the device it will be seen that it makes no difference which end is engaged by the finger and pressed.

In actual practice a plurality of the removable strips 13 would be provided so that they may be replaced when worn and it will be observed that the tongues 12 will hold these strips firmly in position and yet in such a way that they may be removed and replaced when necessary.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising a shuck formed as a rectangular casing, abrasive strip retaining means on the sides of said shuck, retaining lugs formed at the opposite ends of the shuck, a tray slidably disposed within the shuck and of less depth than the latter whereby to define a space between the bottom of the tray and the shuck, a spring of serpentine form disposed within said space and having its

endmost convolutions engaging against said lugs, and the end walls of the tray being recessed for the accommodation of said lugs and to define at each end of the tray spaced lugs likewise engaging the endmost convolutions of the spring. 30

2. A match box of the character described comprising a shuck and a tray co-extensive in length, the tray being of less depth than the shuck whereby to define a space between the bottom of the tray and the shuck, a spring located within said space, and lugs on the ends of the tray engaging the ends of the spring. 35

3. A match box of the character described comprising a shuck formed at its ends with retaining lugs, a tray slidable within the shuck and of less depth than the shuck whereby to define a space between its bottom and the bottom of the latter, a spring disposed within said space and engaging said lugs, and lugs formed on the ends of the tray at the sides of the lugs on the shuck. 40

In testimony whereof I affix my signature. 45

RAMON GONZALEZ. 50
